UNITED STATES PATENT OFFICE.

AUGUST PUTSCH, OF SOUTH BETHLEHEM, PENNSYLVANIA, ASSIGNOR OF ONE-HALF
TO F. O. DETTMANN, OF NEW YORK, N. Y.

VERTICAL COKE-OVEN.

1,292,874.

Specification of Letters Patent. Patented Jan. 28, 1919.

Application filed June 4, 1915. Serial No. 32,040.

To all whom it may concern:

Be it known that I, AUGUST PUTSCH, a citizen of the German Empire, and resident of South Bethlehem, county of Northampton, 5 ton, and State of Pennsylvania, have invented certain new and useful Improvements in Vertical Coke-Ovens, of which the following is a specification.

According to the usual practice coke ovens 10 are built horizontally, and being thus spread over considerable area are subject to certain defects as to economy of operation. The object of my invention is to reduce the floor area required and at the same time so construct 15 the vertical oven as to increase the efficiency and economy in operation. A further object is to facilitate the removal of the coke by having the oven space trapezoidal, or wider and longer at the bottom than at the top so that the mass of coke will readily drop out. A further object is obtained 20 by providing as the floor of the furnace a trap door adapted to be water sealed to prevent gas leakage. The door is hinged at one end and adapted to drop down when the coke is to be discharged the door thus serving 25 as a chute for directing the discharged coke to the coke wharf where it is handled in the usual manner. Sealing the door with water or sand according to my arrangement 30 makes the door practically self sealing and obviates the use of luting clay which is troublesome and does not always remain effective. In my improved construction I employ 35 vertically arranged regenerators and horizontally arranged air and heating flues. banked one above the other, the latter being connected with the regenerators in such manner that the direction of flow of the air and products of combustion may be reversed 40 at desired intervals. A further improvement relates to the gas admission and air control at the point of combustion.

In the accompanying drawings I have 45 illustrated my improved coke oven embodying the several features of my invention. Figure 1 represents a longitudinal vertical section through one of the ovens; Fig. 2 represents vertical transverse sections along the 50 lines A—A and B—B of Fig. 1; Fig. 3 represents a broken vertical longitudinal section along the line 3—3 of Fig. 2; Fig. 4 is a horizontal section at 4—4 of Fig. 2; Fig. 5 is a similar section taken at 5—5 55 of Fig. 2; and Figs. 6 and 7 represent

graphically the flow of air and products of combustion when operating direct and reverse.

Referring to the drawings 1 represents one of a series of coke ovens arranged vertically. The upper end of the oven at 2 is of less cross sectional area than the lower end at 3 so that a vertical cross section in either direction is a trapezoid. This wedge shape to the oven space facilitates the discharge of the coke when the bottom door is opened. The upper wall of the oven is provided at 4 with an opening for charging the same and a gas exit is provided at 5. The series of ovens is built upon a suitable supporting frame consisting of I-beams or the like 6. The ovens are thus elevated above a chute 7 which is adapted to direct the finished coke to the wharf 8 where it may be removed in the usual manner. The entire bottom of the oven preferably comprises a downwardly opening trap-door 9 lined with fire brick or the like 10. The door 9 is preferably provided with an apron 11 turned up all around the edges to form a trough substantially as indicated in Figs. 1 and 2. The lower opening of the door casing of each oven is provided with a depending flange 12 adapted to lie centrally of the trough or groove 11 of the door and thereby form a seal which may be completed by filling the trough 11 with water or sand. If water is used suitable supply pipes (not shown) may be provided for filling the seal troughs 11 of the several doors. The doors 12 are preferably of cast iron and each provided with a pair of forwardly extending ears 13 whereby the doors are pivoted at 14 so that when each door is dropped it will lie upon and coöperate with the chute 7. The other end of each of the doors is preferably provided with a pair of projecting arms or lugs 15 to which suitable cables or ropes 16 are attached for lifting and closing the respective doors. It is desirable that, when 100 closed, the doors 9 be held firmly in place so that the seal in the channel or trough 11 will not become broken. For this purpose any suitable wedging or clamping means may be employed such as the wedge 17 driven between the door and a bar or rod 18 suitably supported from the I-beams 6, substantially as shown in Figs. 1 and 2 of the drawings.

The wedge 17 is preferably made of spring 110

steel in open formation so that the spring of the wedge will hold it in place.

The several ovens of the series are arranged side by side and separated by cellular partitions provided with a plurality of horizontal tubular conduits or flues for the circulation of air and the products of combustion. The ends of the flues of each cell are connected with flues connected with regenerators of the checker brick type which in the present case are arranged vertically.

The regenerators 20 are located in front of the ovens 1, and each is provided with a dampered air inlet pipe 21. Flues 22 are connected with the tops of the regenerators, and each may alternately serve to conduct hot air or the hot products of combustion, as will be more fully explained hereinafter. Each regenerator 20 is also adapted to communicate with a conduit 23 connected with the smoke stack or chimney for carrying off the products of combustion.

The flues 22 are each provided with branch pipes 24 alternating on each side thereof, "sow and pig" fashion, the branch pipes of adjacent flues 22 interlacing or alternating as indicated in Fig. 2 of the drawings. Each branch flue 24 communicates with a horizontal flue 25 in the dividing wall between adjacent ovens 1. The flue 25 is central horizontally of two other flues 26 with which it communicates by a transverse opening 27, see Figs. 4 and 5. The parallel side flues 26 communicate at their forward ends with the corresponding flues 26 above or below in the same cell (see Fig. 3) these in turn communicating with another central flue 25 which in turn connects with one of the branch pipes 24 of the adjacent flue 22. Each series of communicating flues 25-26 are separated from the adjoining series by a solid partition 28 whereby each cell becomes a separate heating unit in which the circulation of air and the products of combustion may take place in either direction according to which regenerator is being heated. It will thus be seen that in each cell the flue connection is continuous from the air inlet pipe 21 through one generator 20, flue 22 branch 24 and returns through the branch 24 and flue 22 connected with the adjacent regenerator 20 and thence to the chimney through the flue 23, the first regenerator being adapted 55 to heat the incoming air and the other being heated by the products of combustion. After a predetermined period of operation in this manner the direction of circulation is reversed and the first regenerator is re-heated by the products of combustion.

The gas for heating the oven is preferably introduced at the cross or branch flues 27 by two pipes 29 branching from a main 30, and by two pipes 31 from a main 32, 65 the two pipes or burners 29 and the two

similar pipes or burners 31 being directed into the two flues 26 above and below the dividing wall 33 respectively. It will be seen that the gas may be admitted to one or the other sets of burners 29, or 31, according to the direction of flow of the air and products of combustion. The gas burners or pipes 29 and 31 are preferably centrally arranged in the ends of the flues 26 substantially as shown in Fig. 3 and removable air nozzles 34 are inserted above and below the burners. The wall back of the burners is also preferably provided with holes opposite the air nozzles 34 which are adapted to be closed by bricks 35. The nozzles 34 are preferably seated in tapered holes and nozzles of various sizes are provided to interchangeably fit the tapered holes so that the amount of air admitted may be varied. By removing the bricks 35 the nozzles may be changed when desired or the operation of the burner inspected.

In order to more clearly understand the operation, the circulation of the air and the products of combustion are indicated by arrows on some of the sectional drawings but to more clearly illustrate it, both direct and reverse, two diagrammatic views are given in Figs. 6 and 7 and letters are used to designate the different flues and associated parts. Fig. 6 shows direct circulation, that is, air enters the air passage 21 at *c*, and passes through the regenerator B (20) where it is heated; thence through the flue *d* (22 and branch 24) into the horizontal flue *e* (25) to the transverse flues *f* (27) where the gas is introduced through the burners or pipes (29) from the main *a* (30). The gas being ignited, the products of combustion return in the flues *b* (26) along the walls of the oven and at the forward end turn up and traverse the flues *b'* (26 above the septum 33) turn at *f'* in a horizontal plane and enter the central flue *e'* thence through *d'* (branch 24 and flue 22) to the regenerator B' (20), through which it passes and then by tunnel *g* (23) enters the chimney. Fig. 7 indicates the currents when the apparatus is reversed and the air enters through *B'*, *d'*, *e'*, and meets the gas at *f'*, the products of combustion traversing flues *b'* to *b* turns at *f* into *e* thence through *d*, *B* and *g* to the chimney. During the reverse operation the gas is supplied from the main *a'* (32) through the upper pair of burners (31).

When the coking process is completed the wedges 17 and bar 18 are removed and the doors 9-10 lowered, thus allowing the coke to drop out and slide down the door and chute to the wharf or platform 8, the trapezoidal shape of the oven facilitating the exit of the coke therefrom.

It will be understood that various modifications in the specific details of construction may be made without departing from

the spirit and scope of my invention as defined in the appended claims.

I claim:

1. A vertically arranged coke oven of greater cross-sectional area at the bottom than at the top, regenerators, horizontally arranged independent groups of heating flues in the walls of said oven, the inlet and outlet ends of the flues in each group being located in common vertical planes extending lengthwise of the flues, means for connecting the inlet ends of said flues with one of said regenerators and means for connecting the outlet ends with another of said regenerators, whereby one regenerator heats the incoming air while another regenerator is heated by the outflowing products of combustion. 70
2. A vertically arranged coke oven of trapezoidal shape, the larger rectangular area being at the bottom, vertically disposed regenerators, horizontally arranged heating flues in the walls of said oven, said flues being arranged in groups with the inlet and outlet ends of each group connected respectively with one of said regenerators and located in common vertical planes extending lengthwise of said flues whereby one of said regenerators heats the incoming air while the other is heated by the outflowing products of combustion. 75
3. A series of vertically arranged coke ovens of trapezoidal shape, the larger rectangular areas being at the bottoms, vertically disposed regenerators, a plurality of horizontally arranged flues in the walls of said ovens, said flues being arranged between two ovens in groups each of which comprises a pair of combustion flues each lying adjacent to and along one of said ovens and an intermediate flue lying between and connected with said combustion flues and flues leading respectively from the inlet and outlet of each group of horizontal flues to one of said regenerators whereby one regenerator heats the incoming air while the other is heated by the outflowing products of combustion. 80
4. In a vertical regenerative coke oven, two generators, internal horizontal flues located one above the other, between heating flues in the same horizontal plane in the oven wall, said flues being arranged in independent groups and operatively connected with said generators. 85
5. In a plurality of vertical regenerative coke ovens, a plurality of vertical regenerators, one for each oven, a plurality of groups of internal horizontal flues located one above the other between corresponding heating flues in the same horizontal plane in the walls between adjacent ovens, the several groups being independently connected with two regenerators substantially as described. 90
6. In a plurality of vertical regenerative coke ovens, a plurality of vertical regenera- 95
- tors, one for each oven, a plurality of groups of internal horizontal flues located one above the other between corresponding heating flues in the same horizontal plane in the walls between adjacent ovens, means for supplying fuel gas to each group and independent means for regulating the flow of air and waste gases through each group of flues and thereby control the temperature at different horizontal levels, the several groups being independently connected with two regenerators, substantially as described. 100
7. The combination of a coke oven provided with flues in the walls thereof, gas burners communicating with said flues, and air inlet nozzles removably located in co-operating pairs at the inlet ends of said flues, said air inlet nozzles being independently interchangeable to vary the air supply to said flues. 105
8. A coke oven or the like, having chambers and heating walls adjacent thereto, said walls containing flues arranged in groups, each group comprising two U-shaped combustion flues each of which has its parallel members located one above the other and ranging lengthwise of said wall, the upper and lower members of one combustion flue being arranged in the same horizontal planes with the upper and lower members respectively of the other combustion flue of the same group, additional longitudinal flues located between the upper members of said combustion flues and between the lower members of said combustion flues respectively, 110 and connected at one end with the adjacent ends of both combustion flues, an upright flue connected with the other ends of the lower additional longitudinal flues of the several groups, another upright flue connected with the other ends of the upper additional longitudinal flues of the several groups, regenerators, means for connecting them alternately with said upright flues, and separate mains for supplying fuel to the ends of the upper and the lower members respectively of the combustion flues. 115
9. A coke oven or the like, having chambers and heating walls separating them, said walls containing flues arranged in groups, each group comprising two U-shaped combustion flues each of which has its parallel members located one above the other and ranging lengthwise of said walls, the upper and the lower members of one combustion flue being arranged in the same horizontal planes with the upper and the lower members respectively of the other combustion flue of the same group, additional longitudinal flues located between the upper members of said combustion flues and between the lower members of said combustion flues respectively, and connected at one end with the adjacent ends of both combustion flues, upright flues each connected with the other ends of 120
- 125
- 130

the lower additional longitudinal flues of the several groups in one heating wall and with the other ends of the upper additional longitudinal flues of the several groups in another heating wall, and separately controllable means for supplying fuel to the upper and the lower members respectively of the combustion flues.

10. A coke oven or the like, having a chamber and a heating wall adjacent thereto, said wall containing a plurality of U-shaped combustion flues whose parallel members are located one above the other, the upper members of adjoining flues in said wall being in the same horizontal plane, and the lower members of adjoining flues in said wall being at the same level, and means including connections between the upper and lower members respectively of adjoining flues for supplying said flues with air and fuel and for carrying away the combustion products.

11. A coke oven or the like, having a chamber and a heating wall adjacent thereto, said wall containing a plurality of longitudinal combustion flues having parallel superposed members connected at one end, the upper members of adjoining flues being at the same level, and the lower members of adjoining flues being in the same horizontal plane, additional longitudinal flues located between

the adjoining upper and lower combustion flue members respectively and at the same levels therewith, and connected at one end with the free ends of the adjacent combustion flue members, means for connecting the other ends of said additional longitudinal flues alternately with a supply of air and with means for carrying away the combustion products, and separately controllable means for supplying fuel to the upper and the lower members respectively of the combustion flues, at their said free ends.

12. A vertically arranged coke oven, regenerators, groups of flues located in the walls of said oven and each comprising an intermediate flue and two outer flues, a connecting means common to all of said flues at one end thereof, and means for connecting each of said intermediate flues with one of said regenerators whereby the incoming air is heated in one regenerator co-incidentally with the heating of the other regenerator by the outflowing products of combustion.

In testimony whereof I have hereunto set my hand in the presence of two subscribing witnesses.

AUGUST PUTSCH.
